MACARONI

Felice Della Femina, Brooklyn, N. Y., assignor to
V. La Rosa & Sons, Inc., Brooklyn, N. Y., a corporation of New York

Application May 26, 1950, Serial No. 10,201

Term of patent 14 years

(Cl. D8—1)

To all whom it may concern:

Be it known that I, Felice Della Femina, a citizen of the United States, residing in Brooklyn, in the county of Kings, State of New York, have invented a new, original, and ornamental Design for Macaroni, which the following is a specification, reference being had to the accompanying drawing, forming part thereof:

I claim:

The ornamental design for macaroni, substantially as shown.

FELICE DELLA FEMINA.
